ATTORNEY.

UNITED STATES PATENT OFFICE.

WILLIAM L. DE HAVEN, OF WICHITA, KANSAS, ASSIGNOR TO JOHN W. MOYLE, OF AUGUSTA, KANSAS.

TOY.

1,400,942.

Specification of Letters Patent.

Patented Dec. 20, 1921.

Application filed February 7, 1921. Serial No. 443,287.

To all whom it may concern:

Be it known that I, WILLIAM L. DE HAVEN, a citizen of the United States, and a resident of Wichita, in the county of Sedgwick and State of Kansas, have invented 5 certain new and useful Improvements in Toys, of which the following is a specification.

My invention relates to a mechanical 10 driven toy, that can be operated in a simple manner, and can be handled ordinarily without destruction to the mechanism, same being housed except the crank by which it is operated.

15 The object of my invention is to provide a simple device for amusement, and one that can be handled and operated by children.

My invention consists further of certain 20 details of construction and arrangement of parts as hereinafter described, and claimed.

Referring to the drawings Figure 1 is a perspective view of the toy with parts broken away for convenience of illustration.

Fig. 2 is a vertical section. A is the box 25 arranged to house the mechanism. B is the trunk of the puppet. C is a crank shaft. D is a belt. E is a roller or pulley mounted on crank shaft F. G is a partition. H is a transparent front of the container. The 30 partition G is partly broken away as shown at I in Fig. 1. b is the head of the puppet. b¹, b², b³ and b⁴ are the arms. b⁵, b⁶, b⁷ and b⁸ are the legs.

Crank shaft C is journaled in the back 35 and partition at the upper end of the container and said shaft is adapted to rotate in said bearings as shown at c², said shaft having a crank the end of which is pivotally connected to the head of the puppet as 40 shown at c¹.

Crank shaft F is journaled in the sides of the container at the lower end being transverse to shaft C, said shaft being adapted 45 to revolve and by means of the belt D shaft C is actuated and the crank of said shaft being attached to the puppet as shown will cause said puppet to oscillate throwing its arms and legs in various directions typifying a dancing posture with the feet striking 50 the floor of the container at times.

It will be readily seen that the shoulder, elbow, hip and knee joints are pivotally connected, making the joints free to move with various gestures during the oscillating motion, which is created by the revolutions of 55 shaft F as heretofore described.

The puppet is held in position, being suspended from the crank on crank shaft C as heretofore described, and is further protected by a glass or other transparent covering, as shown at H, therefore the toy may be tumbled about without serious danger or destruction. 60

I do not confine myself to making my toy of any particular kind of material, as the 65 case may be made of wood, metal, pasteboard or other materials, as may also the puppet. The belt may be made of rubber, cloth or leather.

Having thus described my invention what 70 I claim as new and desire to secure by Letters Patent, is—

1. In a toy, the combination of an upright box having a transparent front and an upright partition spaced behind said 75 front; a horizontal shaft journaled in the walls of the lower part of the box, an exterior hand-crank for rotating said shaft, a drive-belt passing around the upper shaft and said pulley, a crank on the upper shaft between said partition and the transparent 80 front, and an articulated puppet comprising a head, trunk and limbs, the head being freely suspended from the crank on said upper shaft.

2. In a toy, the combination of a box, a 90 horizontal shaft journaled in the end walls of the lower part of the box, an exterior hand-crank for rotating said shaft, a pulley on said shaft within the box, a rotary shaft journaled in the other two walls and extending at right angles to the aforesaid shaft, in the upper portion of the box, a drive-belt passing around the last mentioned shaft and said pulley, a crank-pin on the driven shaft, and an articulated puppet 95 comprising a head, a body, articulated legs and arms, the head being freely suspended from said crank-pin, and the feet of the puppet touching the floor of the box when said crank-pin is at its lowest position. 100

WILLIAM L. DE HAVEN.
